(57) CLAIM

The ornamental design for a small pad holder, as shown and described.

DESCRIPTION

FIG. 1 is a perspective view showing the front, left side and bottom of the small pad holder showing my new design.

FIG. 2 is a front view thereof.

FIG. 3 is a rear view thereof.

FIG. 4 is a right side thereof.

FIG. 5 is a top view thereof; and,

FIG. 6 is a bottom view thereof.

The paper pad depicted by means of broken lines in FIG. 1 has been shown for illustrative purposes only and forms no part of the claimed design.
